UNITED STATES PATENT OFFICE.

JOSEPH ROSENFELD, OF DETROIT, MICHIGAN.

MUFFLER.

1,006,288.

Specification of Letters Patent. Patented Oct. 17, 1911.

Application filed March 18, 1910. Serial No. 550,134.

To all whom it may concern:

Be it known that I, JOSEPH ROSENFELD, a citizen of the United States, residing at Detroit, in the county of Wayne, State of Michigan, have invented certain new and useful Improvements in Mufflers; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to mufflers designed to be worn around the neck, and consists in the formation and association of parts hereinafter more fully set forth and claimed.

20 The object of the invention is to provide a muffler of the character described which will fit closely around the neck without choking and which is of such a character as to render it adjustable for necks of various sizes without loosening or changing the fastening device, the arrangement being such as to enable the lapping points of the muffler at the front to be turned back to expose the collar, if desired.

25 30 The above object is attained by the device illustrated in the accompanying drawings, in which:—

Figure 1 is a plan view of a muffler embodying my invention, the portion thereof which encircles the neck being in the shape of a V. Fig. 2 is a similar view showing the neck piece straight. Fig. 3 is a transverse section through the ends of the muffler showing the detached parts of the 35 glove fastener employed to secure the muffler in position around the neck. Fig. 4 is a sectional view through the ends of the muffler with the parts of the fastener engaged, as when securing the ends of the 40 muffler together. Fig. 5 is an elevation of the muffler as when in use upon the neck of the wearer. Fig. 6 is a similar view showing the adaptability of the muffler to adjust itself to the neck of a large person and still 45 remain closed. Fig. 7 is a view showing how the points on the neck piece may be turned down to expose the collar of the wearer, if desired. Fig. 8 is a view showing the muffler in position before being 50 secured by the fastening means, illustrating 55

the manner in which the points of the neck piece overlap.

Referring to the characters of reference, 1 designates the neck piece which connects the end portions 2 and 3 respectively, said 60 end portions being adapted to hang over the breast of the wearer when the muffler is closed around the neck. The neck piece and end portions are preferably formed integral of knitted or woven fabric. It is 65 preferred to make the neck piece in the form of a V, as shown in Fig. 1, because when so shaped it fits closely and perfectly to the neck and the point of the V which extends downwardly under the coat, assists in retaining the muffler in place. A straight 70 piece however, may be employed, as shown in Fig. 2, but it is not quite so satisfactory. The front edge of the neck piece at each 75 end near the point of juncture with the end piece of the muffler is provided with a projecting point 4. These points overlap when the muffler is placed around the neck, as shown in Figs. 5 and 6 and close the meeting 80 ends of the neck piece at the front above the fastening means 5, comprising the male and female parts of a glove fastener which are secured respectively to the margins of the end portions of the muffler below the 85 points 4. The lapping points 4 close around the neck of the wearer and form a flexible collar for the muffler standing above the fastening means which will conform to the neck and readily adjust itself to necks of various sizes and still maintain the collar 90 of the muffler closed at the front. This arrangement makes it unnecessary to manufacture mufflers having neck pieces of various lengths, as a muffler made in accordance with this invention, will accommodate 95 all wearers.

Mufflers have heretofore been made from which the points 4 of the neck piece have been omitted, and wherein the fastening means have been placed upon the neck piece 100 at the point where the end pieces meet around the neck of the wearer. This arrangement made it necessary to make the mufflers in various sizes for the reason that a muffler whereon the fastening means were 105 placed so as to close the neck piece tightly around the neck of a small person, would render the muffler too tight for the neck of a larger person, and vice versa. With this arrangement the entire range of variation 110

between the smallest and the largest necks is provided for with but one size of muffler, because of the provision for permitting the muffler to adjust itself to the neck of the 5 wearer without causing the meeting ends of the neck piece to separate.

When the muffler is fastened around the neck, as shown in Figs. 5 and 6, the collar and a portion of the tie of the wearer may 10 be exposed by turning the points 4 of the neck piece downwardly, as shown in Fig. 7. The locating of the fastening means below the points, as shown, enables said points to be turned down so as to roll the 15 muffler away from the neck without unfastening it, an arrangement of advantage to the wearer when temporarily entering a warm building, as the neck can thereby be relieved without unfastening the muffler or 20 removing it, the muffler remaining in such position that when going outside, to again protect the neck, it is only necessary to turn up the corners 4 of the neck piece.

It will be noted that the margins of the 25 end portions 2 and 3 lap when the muffler is in position on the neck of the wearer. To hold the lapped margins of the end portions together at their lower end, the margin of the end portion 2 is provided with a projecting tongue 6, which is preferably V-shaped and which is adapted to enter the button-hole like aperture 7 in the margin of

the end portion 3. When the tongue 6 is drawn through said aperture, the clinging nature of the fibrous material of which the 35 muffler is formed, will offer such resistance to the withdrawal of the tongue as to prevent the separation of the lower ends of the muffler while being worn, affording a simple and efficient fastening means. 40

Having thus fully set forth my invention, what I claim as new and desire to secure by Letters Patent, is:—

A muffler comprising a neck piece and relatively wide end portions connected by 45 said neck piece to form a flat structure, the neck piece having at its terminals contiguous to the end pieces transversely projecting points in the plane of the connected end pieces and extending beyond the front margins thereof, said points being adapted to overlap at the juncture of the end and neck pieces when the muffler is being worn, and fastening means for joining the end portions located on said end portions entirely below 50 the portion of the muffler which embraces the neck of the wearer. 55

In testimony whereof, I sign this specification in the presence of two witnesses.

JOSEPH ROSENFELD.
